UNITED STATES PATENT OFFICE.

SOLOMON M. KEMP, OF BALTIMORE, MARYLAND, ASSIGNOR OF TWO-THIRDS
TO EDWARD S. STUBBS AND WILLIAM T. HENDERSON, OF SAME PLACE.

HEATING-DRUM.

SPECIFICATION forming part of Letters Patent No. 483,116, dated September 20, 1892.

Application filed March 30, 1892. Serial No. 427,001. (No model.)

To all whom it may concern:

Be it known that I, SOLOMON M. KEMP, a citizen of the United States, residing at Baltimore city, in the State of Maryland, have 5 invented certain new and useful Improvements in Heating-Drums, of which the following is a specification.

This invention relates to an improved heating-drum for utilizing the heat produced by 10 an ordinary burner—such as a lamp, gas-burner, or the like—to warm a room.

With this object in view the invention consists in the novel features of construction and combination of parts hereinafter described.

15 The invention is illustrated in the accompanying drawings, wherein—

Figure 1 shows a front elevation of the complete apparatus; Fig. 2, a vertical section thereof; Fig. 3, a horizontal section on line 20 3 3 of Fig. 1; Fig. 4, a bottom view of the drum cap or cover.

A curved plate A stands on a suitable base B and is provided with a top cover C, having a central circular opening a and an upward-extending flange b about the same. This 25 plate A constitutes an open-front shell or casing for containing the burner, which in the present instance is a lamp D of the well-known central-draft type and stands on the base B. The shell A has a horizontal partition E, with a slot D' to receive the neck of the lamp, and a slide F works in guide-strips F', secured at opposite sides of said slot. This slide fits around the outer side of the lamp-neck and serves to hold the lamp steady.

The partition and slide divide the lower part of the casing, which contains the globe of the lamp, from the upper part, containing the burner. A series of openings c in the lower 35 part of the case insure an ample supply of air to keep the lamp-globe cool, and another series of openings d above the partition E supply air to the burner. A hood d' is secured on the outer side of the casing, just

40 above the latter series of openings, and serves to direct the fresh air at the bottom of the room into the openings. A cylindrical drum G is mounted on the top of the casing A, and its bottom has an internal conical cap H, 45 which fits over the flange b. A coiled pipe I leads out of this conical cap to the top parts

of the drum, where it points toward the front, and the drum has a line of openings e at the front opposite the mouth f of this coil. A cover J is fitted to the top of the drum, and 55 an inclined deflector-plate K is fastened in this cover with its lower part at the rear of the same and its highest part at the front. This plate appears as a false cover for the drum. A number of pipes L open into the 60 lower part of the drum and extend downward on the outside of the casing A to the lower part of the same, where they have flared mouths g. These pipes are perforated throughout their length, the perforations h 65 being made in four sides, as shown. The drum and pipes are removable from the case A, and each pipe is held at its lower end between staples i on the casing by a hasp j, which takes around the pipe and is hinged 70 in one staple and hooks into the other, as seen in Figs. 1 and 3.

The operation is as follows: Whatever heat and light radiates from the burner laterally is thrown outward by the plate A, which 75 thus serves as a reflector. It is therefore given a parabolic curve, as seen in Fig. 3. The greatest heat of the burner and the products of combustion therewith pass directly upward into the conical cap H and thence 80 through the coil I and exit therefrom at the mouth f. The heat which radiates from the coil during the passage of the products of combustion therethrough heats the air contained in the drum. This heated air, together 85 with that which emanates from the mouth of the coil, issues through the openings e into the room. At the same time the colder air near the floor passes up through the pipes L, entering the same through the flared mouths 90 g and perforations h, and supplies the drum with air to be heated and in turn supplied to the room. The inclined plate K serves to deflect the heated air in the drum toward the exit-openings e. By my arrangement a room 95 of average size may be thoroughly warmed and kept at a comfortable temperature with an ordinary lamp, gas-burner, or similar heat-producing device. It will be found very useful in bath-rooms and similar places, which 100 are not usually provided with heaters.

It is evident the construction here shown

may be varied without departing from the spirit and scope of the invention.

Having thus described my invention, what I claim as new, and desire to secure by Letters 5 Patent, is—

1. The combination of a suitable casing or shell for containing a burner, a drum located above the burner and having an inlet for air at the lower part and an outlet-opening at 10 the upper part, and a coil in the drum, having its lower end open and over the burner and its upper end open and within the drum and directed toward the outlet-opening in the latter.
- 15 2. The combination of a suitable casing or shell for containing a burner, a drum located above the same and containing a coil having its inlet end over the burner and its outlet at the upper part of the drum, the latter provided with an inlet for air at the lower part and an outlet at the upper part, a cover fitting the top of the drum, and a deflector-plate in said cover.
- 20 3. The combination of a suitable casing or shell for containing a burner, a drum located above the same and containing a coil having

its inlet end over the burner and its outlet at the upper part of the drum, the latter provided with an outlet for air at the upper part, and perforated pipes opening into the lower 30 part of the drum and extending downward therefrom and open at the lower ends.

4. The combination of a suitable casing or shell for containing a burner, a drum located above the same and containing a coil having 35 its inlet end over the burner and its outlet at the upper part of the drum, the latter provided with an outlet for air at the upper part, perforated pipes opening into the lower part of the drum and extending downward adjacent to the exterior of the casing or shell and open at their lower ends, and hinged hasps on the said casing and arranged to take around and hold the pipes, in the manner described.

In testimony whereof I affix my signature in the presence of two witnesses.

SOLOMON M. KEMP.
